HAIR DRYER HOOD

George Leo Paul Nawroth, 667 Hamilton St.,
Preston, Ontario, Canada

Filed Apr. 26, 1965, Ser. No. 84,964

Term of patent 7 years

(Cl. D86—10)

FIG. 1

FIG. 2

FIG. 3

FIG. 4

FIG. 1 is a front perspective view of a hair dryer showing my new design;

FIGURE 2 is a bottom perspective view thereof;

FIGURE 3 is a right side elevational view; and

FIGURE 4 is a top plan view thereof.

I claim:

The ornamental design for a hair dryer hood, as shown.
